KNITTING MACHINE.

Application filed June 22, 1921. Serial No. 479,512.

My invention relates generally to knitting machines and more especially to knitting machines employed in the manufacture of hosiery.

5 In the knitting of hosiery as ordinarily practiced, it is customary to reinforce those portions of a stocking which are liable to the greatest wear. Such reinforcement is secured by supplying to the knitting needles, 10 an auxiliary or splicing yarn in addition to the main or body yarn which is dominant in stocking fabric.

The main object of my invention is to make it possible to render the reinforced 15 portion of the knitted web serviceable, not only from the standpoint of utility, but in an ornamental capacity as well, so as to enhance the attractiveness and saleability of the stocking. This desideratum I attain by 20 governing the duration of the active periods of an intermittently operative auxiliary or splicing yarn feed so that the range of feeding, or in other words, the number of needles supplied with the reinforcing yarn, is varied 25 concurrently with the production of the knitted web. In this way, for example, the portion at the back of the stocking ankle directly above the heel, ordinarily known as the "high heel" reinforcement, may be given 30 an ornamental tapered configuration, beginning coextensively in width with the heel and terminating in a point in what may be conveniently termed the median line at the back of the stocking structure.

35 Other objects and attendant advantages of my invention will become readily apparent from the detailed description which follows.

In the drawings, Fig. I, is an elevation of 40 a knitting machine conveniently embodying my invention, portions thereof being shown in section for the purpose of setting forth certain important details to the best advantage.

45 Fig. II, is a perspective illustration of the greater part of the structure as viewed from the right of Fig. I.

Figs. III, and IV, are diagrammatic detail views showing for the purposes of comparison and in different positions, two co- 50 operative elements of the mechanism whereby the splicing yarn feed is actuated.

55 Fig. V, is a diagrammatic illustration of one side of the foot of a stocking showing, by way of example, an ornamental high heel reinforcement capable of being produced by

aid of my invention, the other side being, of course, a duplicate in construction.

The machine herein shown is a circular stocking knitter, which, it will be observed, is generally of well known construction. Its 60 needle cylinder 1 is appropriately mounted for rotation in a projecting extension 2 of a plate 3 which forms a part of a housing frame 4. Said frame serves to support the various operative mechanisms of the machine, and is mounted upon a sub-structure 5 whereby it is in turn supported at a convenient height from the floor. Motion is imparted to the needle cylinder 1 through a bevel gear 6 secured to the inner end of 65 a main driving shaft 7 which is provided at its opposite extremity with a series of pulleys 8—8 adapted for co-ordination with any suitable source of motive power.

70 As is common to hosiery knitters, appropriate mechanism is provided for effecting either rotary or oscillatory motion of the needle cylinder in producing stockings after well known and approved practice. In the present instance, this mechanism includes a 75 clutch 9, adapted to be shifted by a grooved drum 10 fixed upon a shaft 11 which is rotated under the drive of a ratchet wheel 12. Pawling of the ratchet wheel 12 is subject to the control of a pattern chain 13 which runs 80 about a sprocket wheel 14 mounted for free rotation upon the shaft 11. Said sprocket wheel is either formed integrally with, or is attached to a ratchet wheel 15 adapted to be 85 picked by means of a suitable pawl not shown.

90 The knitting needles, indicated at 16 in Fig. I, are guided for reciprocation in vertical grooves of the needle cylinder 1 and are subject to appropriate actuating cams upon a cam shell or block 17. The machine is equipped with a series of feeds, whereby 95 yarns of different qualities or gauges may be interchanged in the course of the knitting. Amongst these is a feed 18 which supplies a main or body yarn to the needles, and a feed 19 which supplies an auxiliary or 100 splicing yarn during certain periods of the knitting of a stocking. Said feeds are freely fulcrumed about a common pivot rod 20 secured in upstanding lugs 21 of a ring 22 which surrounds the top of a needle cylinder, said ring being hinged at 23 to a stationary 105 bracket 24. Associated with each yarn feed 25 is a thrust bar 25, which engages the feed 110

from beneath to swing the same upwardly about its fulcrum in opposition to the pull of a spring 26 when it is to be rendered inoperative. The several thrust bars 25 are 5 guided adjacent their upper ends, in a slotted element 27, and similarly near their lower ends, in a slotted plate 28 which is secured to a fixed cylindrical bar 29 extending laterally from the machine frame 4. In 10 introduction of the various yarn feeds, or substitution of one for the other, is controlled by a master drum 30 having a series of peripheral cam segments 31—31 designed to co-operate respectively with the lower ends 15 of the thrust bars 25. The cam drum 30, is, in its turn, subject to the control of the pattern chain 13 rotative motion being imparted thereto from the shaft 11 through a transmission train comprising the intermeshing gears 32, 33 and 34, see Fig. I.

While the splicing yarn feed 19, like its fellows, is subject to the master control of the drum 30, its behavior, when released to activity in reinforcing certain portions of 25 the stocking, is however subject to the sub-control of a mechanism which effects its intermittent action, and which moreover so governs the duration of its periods of activity as to effect variation in the range of 30 feeding, or in other words, variation in the number of needles supplied as the knitting proceeds. It is with this mechanism that my invention is particularly concerned, and which I will now proceed to describe in 35 detail.

Mounted for free oscillation about a shaft 35 is an arm 36 having attached to its upper end, a roller 37 which runs in contact with the edge of a cam 38 secured to the 40 front face of the bevel gear 6 on the main driving shaft 7 previously referred to. The arm 36 is held in positive engagement with the cam 38 by a coiled spring 39, and has, at one side, a cam 40, which, owing to the 45 oscillatory movements of said arm induced by the rotary cam 38, is constantly reciprocated beneath the right hand end 41 of the lever 42. Said lever is fulcrumed at 43 to the back of a movable support in the 50 form of a link 45, and its opposite end is slotted as indicated at 46 for the purpose of receiving in said slot one end of a second or motion translating lever 47 shown to best 55 advantage in Fig. II. The lever 47 is pivoted intermediate its ends, to an upturned lug 48 of a fixed plate 50 secured as an extension to the guide plate 28 for the yarn feed thrust bars 25. The left hand end of the lever 47 (Fig. II) engages the under 60 side of a projection 51 on the thrust bar 25 which actuates the splicing yarn feed 19. Pausing for a moment at this juncture to refer to the diagrammatic showing of Fig. IV, it will be noted that upon each 65 movement of the cam 40 to the left, the co-

operative end 41 of the lever 42 is permitted to drop to an extent limited by the engagement of the undercut edge or bight 52 of the lever with said cam 40, the motion thus obtained being imparted, through the 70 lever 47, to the thrust bar 25 of the auxiliary or splicing yarn feed with the result that for each revolution of the needle cylinder, said feed is allowed to descend into action under the pull of its spring 26. The 75 duration of such active periods of the yarn feed will obviously be determined by the positions of the end 41 of the lever 42 with respect to the field or path of reciprocation of the cam 40. Thus, in order that the periods of activity of the auxiliary or splicing yarn feed 19 may be varied, we have provided for the shifting of the link 45 which supports the fulcrum of the lever 42. One 80 end of said link is accordingly pivotally attached to a shifter arm 55 and the opposite end supported through the instrumentality of a screw stud 56 which is guided for movement within a horizontal slot in the upturned portion 57 of the plate 50 already 85 mentioned. The shifter arm 55 is freely fulcrumed to the shaft 35 directly adjacent the oscillating arm 36, and held from displacement by a collar 58. To the lower end of the shifter arm 55 is attached a roller 90 60 which cooperates with a rotary cam 61 which may be called a pattern cam. Said cam is secured to the front face of a ratchet wheel 62 adapted to rotate independently 95 about the shaft 11, as an axis. The ratchet wheel is racked, a tooth at a time, by a pawl 63, the latter receiving its motion by virtue of its being pivotally connected at 64, to the oscillating arm 36 or to a radial extension of the hub portion of said arm. 100 A spring 65 serves to maintain the pawl 63 at all times in positive engagement with the ratchet wheel and retrograde movement of the latter is prevented by a safety detent in the form of a leaf spring 66 extending 105 from a fixed point of anchorage, as clearly shown in Fig. II. After having made a complete revolution, the rotary cam 61 comes to rest automatically by reason of the existence of a blank space 70 amongst the 110 teeth of the ratchet wheel 62 within which the pawl 63 is allowed to play idly until movement of the ratchet is initiated. This movement I prefer to bring about under 115 control of the pattern chain 13, and since the rotation of the shaft 11 is directly subject to such control, the gear 32, secured thereto is therefore employed as a convenient means to this end. Said gear is accordingly, provided with an outstanding stud 120 71, which, when the gear is shifted, engages a similar stud 72 projecting rearwardly from the ratchet cam 61.

In the present connection, I have shown my invention as adapted for the production 130

of an ornamental high heel reinforcement such as shown at 75 in Fig. V. This reinforcement, as suggested diagrammatically in the illustration, is coextensive in width 5 with the top of the heel, and gradually tapers upwardly, in perfect symmetry at opposite sides of the stocking, toward a point 76 in the median line at the back of the latter. With this structure in mind, the 10 operations of the machine in producing the same may be briefly described as follows:

Let it be assumed that the leg of the stocking has been knit in a manner well known to those skilled in the art of producing seamless hosiery until the region has been reached where reinforcement of the high heel is to begin. At this time, a special or high link 15 on the pattern chain 13 causes the ratchet wheel 12 to be pawled with the result that the gear 32 is shifted sufficiently to advance the stud 71 to engage and shift the stud 72 and the ratchet wheel 62. This will serve in turn, to advance the blank space 70 of the ratchet beyond the province of the pawl 63 20 whereupon the latter immediately begins to pick the ratchet tooth by tooth. When the ratchet wheel 62 has been progressed sufficiently to advance the high portion of the attached rotary cam 61 to position beneath the roller 60 on the lower end of the shifter arm 55, the pattern chain 13, again functions 25 to bring about the shifting of the master drum 30 to release the thrust rod 25 of the auxiliary or reinforcing yarn feed 19. The relative positions of the various parts of the machine at this stage are those illustrated 30 in the drawings. From Fig. III, it will be apparent that the position of the end 41 of the lever 42 is such that the cam 40, notwithstanding reciprocation, will be ineffective 35 in inducing motion of the lever, as a consequence of which actuation of the splicing yarn feed 19 does not begin immediately. However, as the rotation of the rotary cam 45 40 continues, the end of the lever 42 will be advanced in the direction of the arrow in Fig. III until it drops off the cam 40, so that the auxiliary or splicing yarn feed 19 will be permitted to become active momentarily to feed yarn to one or two needles. By reason 50 of the spiral configuration of the cam 61, the duration of the periods of activity of the auxiliary yarn feed 19, will be increased gradually course for course of the knitting. The number of needles fed is thus 55 correspondingly increased, until the low point in the cam 61 has reached a position beneath the roller 60 of the shifter arm 55, when approximately half the series of 60 needles is being fed. The relation of the lever 42 and the reciprocating cam 40 at this stage is shown in Fig. IV. When this point has been reached, the roller 60 of the arm 55 will come to rest within the low point 65 of the cam, since the pawl 63 will at this

time play idly within the blank space 70 of the ratchet wheel 62. Contemporaneously with the cessation of the racking of the ratchet wheel 62, the pattern chain 13 causes rotary progression of the drum 10 to shift 70 the clutch 9, whereupon the needle cylinder 1 is oscillated and the heel of the stocking produced by narrowing and widening in the known manner. In knitting the reinforcement of the stocking sole, the cam 61 of the 75 actuating and governing mechanism for the auxiliary yarn feed remains in the idle position last described so that in producing this portion of the web, the yarn is supplied throughout to a constant number or approximately half of the series of needles as suggested in the diagrammatic illustration of the stocking foot in Fig. V. After the stocking is completely formed the transverse connecting threads of the splicing yarn which 80 intersect the channel of the tubular product are trimmed close to the inner surface of the fabric and the ends of the splicing yarn remaining in the fabric, define, with relation to each other, a pair of diverging lines which 85 extend at an angle to the wales of the body yarn as shown in Fig. V. These lines defining the tapering wear resisting area begin at the remote terminals of the heel sutures and converge to a meeting point located on 90 the rear medial line of the leg portion.

While I have shown and described my invention as being particularly applicable to the production of an ornamental high heel reinforcement, it will be obvious that the configuration of the cam 61 and its time of 100 operation may be predetermined to effect production with equal facility of ornamental effects in other parts of the stocking structure.

Having thus described my invention, I claim:

1. In a knitting machine, the combination of a series of knitting needles; a feed adapted to supply auxiliary or splicing yarn to the needles; a pivoted lever co-ordinated with the yarn feed; a reciprocating cam effective upon the lever in causing the yarn feed to be moved intermittently into and out of activity with respect to the needles; and governing means for relatively shifting the lever and the cam to effect variation in the periods of activity of the yarn feed with corresponding variation in the number of needles fed as the knitting proceeds.

2. In a knitting machine, the combination of a series of knitting needles; a feed adapted to supply auxiliary or splicing yarn to the needles; a pivoted lever co-ordinated with the yarn feed; an oscillating arm carrying a cam adapted to co-operate with the aforesaid lever in causing the yarn feed to be moved intermittently into and out of activity with respect to the needles; and governing means for shifting the position

of the lever with respect to its actuating cam to effect variation in the periods of activity of the yarn feed with corresponding variation in the number of needles fed as the knitting proceeds.

3. In a knitting machine, the combination of a series of knitting needles; a feed adapted to supply auxiliary or splicing yarn to the needles; a pivoted lever co-ordinated with the yarn feed; an oscillating arm carrying a cam adapted to co-operate with the aforesaid lever in causing the yarn feed to be moved intermittently into and out of activity with respect to the needles; a shiftable support whereto the lever is fulcrumed; and means for shifting the support to effect changes in the operative relation between the lever and the oscillating cam for the purpose of bringing about variation in the periods of activity of the yarn feed with corresponding variation in the number of needles fed as the knitting proceeds.

4. In a knitting machine, the combination of a series of knitting needles; a feed adapted to supply auxiliary or splicing yarn to the needles; a pivoted lever co-ordinated with the yarn feed; an oscillating arm carrying a cam adapted to co-operate with the aforesaid lever in causing the yarn feed to be moved intermittently into and out of activity with respect to the needles; and governing means for shifting the position of the lever with respect to its actuating cam to effect variation in the periods of activity of the yarn feed with corresponding variation in the number of needles fed as the knitting proceeds, including a rotary cam, and means for controlling the movement of the said rotary cam.

5. In a knitting machine, the combination of a series of knitting needles; a feed adapted to supply auxiliary or splicing yarn to the needles; a pivoted lever co-ordinated with the yarn feed; an oscillating arm carrying a cam adapted to co-operate with the aforesaid lever in causing the yarn feed to be moved intermittently into and out of activity with respect to the needles; and governing means for shifting the position of the lever with respect to its actuating cam to effect variation in the periods of activity of the yarn feed with corresponding variation in the number of needles fed as the knitting proceeds, including a rotary cam capable of coming to rest automatically after having rotated to a predetermined extent; and means for initiating the movements of said rotary cam.

6. In a knitting machine, the combination of a series of knitting needles; a feed adapted to supply auxiliary or splicing yarn to the needles; a pivoted lever co-ordinated with the yarn feed; an oscillating arm carrying a cam adapted to co-operate with the

aforesaid lever in causing the yarn feed to be moved intermittently into and out of activity with respect to the needles; and governing means for shifting the position of the lever with respect to its actuating cam to effect variation in the periods of activity of the yarn feed with corresponding variation in the number of needles fed as the knitting proceeds, including a rotary cam; a ratchet wheel for driving said rotary cam, said ratchet having a blank space amongst its teeth wherein a co-operative pawl may idle without effecting rotative movement of the ratchet; and control means for initiating movement of the ratchet in advancing a blank space of the latter beyond the province of the aforesaid pawl.

7. A circular knitting machine, comprising a needle cylinder; a series of knitting needles carried thereby; a feed for supplying auxiliary or splicing yarn to the needles; a pivoted lever co-ordinated with the yarn feed; a cam reciprocating in synchronism with the rotations of the needle cylinder, said cam being adapted to co-operate with the aforesaid lever in causing the yarn feed to be moved intermittently into and out of activity with respect to the needles; in combination with governing means for shifting the position of the lever with respect to its actuating cam to effect variation in the period of activity of the yarn feed with corresponding variation in the number of needles fed as the knitting proceeds, including a shifter arm; a rotary cam associated with the shifter arm; a ratchet wheel for driving the rotary cam; and a pawl for picking the ratchet, said pawl deriving its motion from the aforesaid oscillating arm.

8. A mechanism for controlling a yarn feed finger of a circular knitting machine, comprising two members with coacting faces, one of which is cammed, and means for reciprocating one of said members with relation to the other in harmony with the rotation of the knitting head, in combination with a pattern cam and means whereby the pattern cam may vary the relation of one of said members to the other, to thereby vary at different courses the number of needles taking yarn from said yarn finger.

9. A circular knitting machine having a series of knitting needles and yarn feeding means, including a splicing yarn feed, a reciprocatory cam for controlling the operation of the said splicing yarn feed, and governing means, cooperating with the said cam, for varying, at different courses, the number of needles taking the splicing yarn.

10. A circular knitting machine having a series of needles and yarn feeding means, including a splicing yarn feed, a pivoted lever co-ordinated with the splicing yarn feed, and a reciprocatory cam effective upon the lever in causing the yarn feed to

- move intermittently into and out of activity with respect to the needles and governing means for relatively shifting the lever and the cam to effect variation in the 5 periods of activity of the yarn feed with corresponding variations in the number of needles fed as the knitting proceeds.
11. In a circular knitting machine having a series of knitting needles and yarn feeding means including a splicing yarn feed, an oscillating arm carrying a cam for controlling the operation of said splicing yarn feed during any one course, and governing means cooperating with the said cam for 10 varying at different courses the number of needles taking the splicing yarn.
12. A circular knitting machine having a series of knitting needles and yarn feeding means including a splicing yarn finger, a cam with means for reciprocating it in 15 harmony with the revolutions of the needles, a pivoted lever adapted to be rocked by said cam and to determine by its rocking the period of activity of said splicing yarn feed during any one course, and means for 20 varying the operative relation between said cam and lever to vary the said period at different courses.
13. A circular knitting machine having a series of knitting needles and yarn feeding means including a splicing yarn feed, an oscillating arm carrying a cam, a pivoted lever adapted to be rocked by said cam and to determine by its rocking the period 25 of activity of said splicing yarn feed during any one course, and means for shifting said lever to change the operative relation between it and the said cam to vary the said period at different courses.
14. A circular knitting machine having a series of knitting needles and yarn feeding means including a splicing yarn feed, an oscillating arm carrying a cam, a pivoted lever adapted to be rocked by said cam 30 and to determine by its rocking the period of activity of said splicing yarn feed during any one course, a pattern cam and means operated thereby for shifting said lever to change its relation to said cam in order to vary the said period at different courses, together with a ratchet wheel having a blank space among its teeth, feed pawl means cooperative with said ratchet for moving said pattern cam, so and mechanism for advancing the ratchet wheel to move the blank space beyond the pawl.
15. A circular knitting machine having a series of knitting needles and yarn feeding means including a splicing yarn feed, an oscillating arm carrying a cam, a pivoted lever adapted to be rocked by said cam and to determine by its rocking the period of activity of said splicing yarn feed during any one course, a pattern cam and means operated thereby for shifting said lever to change its relation to said cam in order to vary the said period at different courses, 45 and means for controlling the movement of said pattern cam.
16. A circular knitting machine having a series of knitting needles and yarn feeding means including a splicing yarn feed, an oscillating arm carrying a cam, a pivoted lever adapted to be rocked by said cam in its reciprocations and to determine by its 50 rocking the period of activity of said splicing yarn feed during any one course, a pattern cam and means operated thereby for shifting said lever to change its relation to said cam in order to vary the said period at different courses and means for moving said pattern cam to shift said lever a predetermined amount and then come to rest.
17. A circular knitting machine having a series of knitting needles and yarn feeding means including a splicing yarn feed, an oscillating arm carrying a cam, a pivoted lever adapted to be rocked by said cam and to determine the period of activity of said 55 splicing yarn feed during any one course, a pattern cam and means operated thereby for shifting said lever to change its relation to said cam in order to vary the said period at different courses, together with a ratchet wheel having a blank space among its teeth, feed pawl means cooperative with said ratchet for moving said pattern cam, so and mechanism for advancing the ratchet wheel to move the blank space beyond the pawl.
- In testimony whereof, I have hereunto signed my name at Philadelphia, Pennsylvania, this 18th day of June, 1921.

EXILIAS E. PAQUETTE.
